FAIRLEIGH S. DICKINSON, OF RUTHERFORD, NEW JERSEY

HYPODERMIC SYRINGE AND NEEDLE THEREFOR

Application filed January 6, 1930. Serial No. 418,962.

The invention relates to surgical instruments of the kind generally known as hypodermic syringes and has for its object to provide means for establishing a reliable connection between the needle and the barrel. The invention, by means of which this result is obtained, involves a needle member as well as a novel structure of the barrel member. Advantages of the invention will be referred 10 to hereinafter.

Although the invention is obviously capable of numerous other forms, I have illustrated preferred embodiments thereof in the accompanying drawings in which Fig. 1 is an 15 elevation of the new syringe; Fig. 2 is an enlarged fragmentary sectional view of the lower portion of Fig. 1; Fig. 3 is a transverse sectional view approximately on line 3-3 of Fig. 2; Fig. 4 is an enlarged side 20 elevation of the needle shown in Fig. 1; Fig. 5 is an enlarged fragmentary side elevation of the lower portion of the barrel of the syringe; Fig. 6 illustrates a right end elevation of the needle shown in Fig. 4; and Fig. 25 7 is a sectional view showing the relation of the needle to the metal sleeve of the barrel member when the needle is in a locked position in the syringe.

Referring to the accompanying drawing 30 by numerals, 1 indicates a syringe preferably made of glass and which is provided with a discharge nozzle 2 tapering on the outer surface so as to readily receive the hub 3 of the needle 4. Heretofore needles have been provided with hubs having bores similar to the bore 4a of hub 3 so as to be readily slipped upon the nozzle 2 and held thereon by friction. A slip joint of this character is very desirable as it provides a good contact between 35 the metal hub and the glass nozzle and holds the needle steady and prevents the entrance of air. When, however, the needle is used with the syringe and depends only upon friction for holding the same in place as has been the practice heretofore, it has been 40 found that the syringe frequently becomes separated from the needle during the operation thereof, particularly where a comparatively heavy fluid is being forced through the 45 needle. This is extremely objectionable and

often dangerous as for example where the surgeon, as a result of such separation, cannot be sure of the exact amount of fluid that he has forced through the needle into the patient.

Nevertheless, although such defects of existing structures have been recognized, no satisfactory remedy has thus far been found. This is in part due to the fact that the needle member may not be fastened in any permanent or troublesome detachable manner to the barrel member but must, at all times, be easily and conveniently separable at will and replaceable by a new needle.

The new invention overcomes all the difficulties and disadvantages of the prior constructions while at the same time retaining all of the advantages thereof. These results are brought about by constructing the needle member so that, while it still may be efficiently utilized in connection with the barrel members of existing syringes of the indicated type in a manner to retain all of the advantages inherent therein, it is specially adapted for use in connection with the barrel 75 of the new syringe which includes means arranged to cooperate with means on the needle, so located with respect to each other as to prevent unintentional separation of the needle and barrel and to emphasize the desirable 80 features which are found in the existing syringes.

In the illustrated example of the invention (Fig. 2), the syringe is provided with a sleeve-carrying element supporting the locking sleeve 5, said element being secured in place in any suitable manner upon the syringe, the method of attachment being such as to withstand separation of the parts under any ordinary conditions to which the syringe 90 is subjected. A preferred method of accomplishing this result is to make the collar 5a of the metal sleeve 5 slightly smaller in internal dimension than the exterior dimension of the ground glass nozzle 2 at its point of connection with said collar 5a, then heating the latter and in its heated condition slipping it upon the relatively cool glass nozzle 2 whereupon as the metal cools a practically permanent connection will be established between 100

the metal sleeve 5a and the glass nozzle 2. The process by which this is accomplished is set forth in my Patent No. 1,727,755. There are other methods of making a proper connection between the sleeve 5 and the syringe 1 but for the purposes of the present case any such connection is the equivalent of the preferred connection above set forth. The hub 3 of the needle is relatively small, light in weight and incapable of being used as a device by itself and is provided with the usual bore 4a, and at that end which is contiguous to the needle 4 is formed with one or more flattened portions or faces 6. Near its opposite end, the hub is provided with one or more faces 7 which as shown may comprise flattened portions on an upstanding flange 8 which in such case is divided into two sections by the flattened or reduced portions 7. The flange 8 is comparatively thin and the two sections thereof which form projecting portions 8' on diametrically opposite sides of the hub, are substantially arc-shaped and each occupy about one-fourth of the complete flange. These projecting portions 8' constitute an example of the means on the needle whereby unintentional separation from the syringe barrel 1 is prevented by cooperation with a co-action means on the locking sleeve 5; thus in the illustrated example said projecting portions 8' act as interlocking cams with the respective spiral cams 9 and 10 arranged interiorly of the locking sleeve 5. The spiral cams 9 and 10 may be termed threads though the action is that of spiral cams, there being two cams to accommodate the two portions 8' which interlock with the cams for holding the hub 3 in substantially the position shown in Fig. 2. It will be understood that other means whereby the needle is connected with the syringe barrel in an equivalent manner so as to be easily detachable and attachable at will and so as to be fixed against unintentional separation may be substituted for the projection portions 8' and the spiral cams 9 and 10. That is to say, any type of devices which cooperate to fix the needle in place in a manner to resist forces developed by the syringe when in use and exerted in a direction parallel with the surface engagement of the needle barrel with the nozzle 2 are within the purview of my claims. When the needle 4 is not in use, it may rest on a supporting surface with one of the flattened faces 7 and the corresponding face 6 positioned in engagement with said supporting surface whereby the needle 4 will be held at an upward inclination with its point elevated for an appreciable distance above the support as shown in Fig. 4. In combining the needle member with the barrel member, the hub is gripped and forced onto the nozzle 2 by a gentle rotation of the hub. The spiral cams 9 and 10 are spaced a sufficient distance apart to permit the hub to freely rotate until it begins to frictionally engage the outer surface of

the nozzle 2 whereupon a final rotation of the hub with very little forward movement will cause the cam portions 8' of the needle member to engage the spiral cams 9 and 10 and act to assure a final perfection of fit and at the same time locking the hub in its perfectly seated condition against accidental removal or accidental loosening. The final rotation of the hub and the resultant cam action between the projections 8' and the spiral cams 9 and 10 jams the parts together so that uncoupling by reverse rotation is resisted to an extent sufficient to prevent unseating of the cams in the ordinary operation of the syringe or unless a special effort sufficient to overcome the resistance is made. At the same time the coupling is not so resistant as to prevent uncoupling with great ease a simple manual operation applied by gripping the needle hub between two fingers of one hand and the barrel with the other hand and imparting reverse rotative movements to these elements. The sleeve 5 in addition to acting as a locking sleeve or member for the hub 3, protects and tends to keep clean the outer surface of the tip or nozzle 2. Even in an exceptional case where the frictional engagement between the tip or nozzle 2 and the hub 3 fails accidentally to be established or a separation takes place from any cause, the cam portions or members 8' will nevertheless co-act with the spiral cams 9 and 10 to hold the hub against disengagement so that the surgeon may without impediment complete the operation of injecting the fluid into the patient.

In cases where it is desired to provide means for specially treating the nozzle with cleansing or disinfecting fluids, the sleeve 5 may be apertured at one or more points as indicated at 11 in Figs. 1-5.

In the embodiment illustrated in the drawings I have shown two such apertures 11 although any number may be used, depending on the particular circumstances.

On the inner wall of sleeve 5 I provide an inwardly extending lug 11' which is herein depicted as being stamped out of and bulged from the metal constituting the sleeve. This lug is adapted to engage a mating slot 12 incorporated in one of the projecting portions of cam 8 and to guide the cam to the starting point of the cam way. Slot 12 is positioned in such relation to the inclined face 13 of the needle point that when the needle is firmly locked in position within sleeve 6, the face 13 and the needle opening 14 are in alignment with a scale 15 which is located on the barrel of the syringe. With this arrangement the doctor or operator does not have to turn the syringe around after he has inserted the needle into a person in order to see the scale as has heretofore been necessary, but the doctor merely has to insert the needle into a person in the usual manner with the inclined face and the needle opening facing

upwardly and then he can read the scale which is in alignment with the inclined face and needle opening without having to turn the syringe around in order to bring the scale 5 into a readable position on the upper side of the barrel of the syringe. It is obvious that by the incorporation of my novel lug and slot construction in a syringe the use of the latter is greatly facilitated and all necessity for 10 twisting and turning the syringe around after insertion into a patient to bring the scale into a readable position is avoided, for the slot and lug construction provides means for positively guiding the needle into a predetermined position with respect to the needle 15 opening so that the needle opening will be in alignment with the scale on the barrel when the needle is in its final locked position. The coupling of the needle to the sleeve of the 20 syringe is also made easy because when the slot is slipped over the lug the cam is in correct position to engage the cam way.

It will be seen that the new needle can be used with equal facility but with improved 25 effect in connection with existing glass syringes without requiring any alteration or modification of the syringe structure. At the same time, the needle member functions still more perfectly when associated with a syringe 30 provided with the described sleeve structure. There is thus provided an improved construction wherein the desirable and beneficial action of the slip joint is retained while at the same time means are presented which will 35 positively lock the needle against slipping off of the syringe when under pressure. The sleeve structure of the new barrel construction is so designed, on the other hand, that it will accommodate any standard existing 40 needle.

So far as the needle member is concerned, it will be seen that a plurality of finger grips 45 are presented which act in the double capacity of finger grips and means for holding the discharge end of the needle from contact with a surface on which it may rest or be mounted, while having also permanent means to adapt 50 the needle to be used with equal facility with a plain glass syringe and with a syringe provided with the novel cooperating member above described.

A further feature of the invention is that it provides a co-acting needle and lock in connection with the nozzle of a syringe whereby 55 the hub of the needle may be forced on the tapering nozzle and be made to firmly engage the same by friction and at the same time become interlocked with the locking member secured to the syringe so that accidental loosening of the needle will not cause its removal 60 from the syringe.

It will also be observed that the relation between the sleeve and barrel is such as to avoid 65 having the metal project over the sides of the barrel, thus avoiding any obstruction to

the complete observation of the entire interior of the barrel.

It is to be observed that the hub of the needle illustrated and described herein is constituted of a relatively thin, light shell of 70 metal, and is made relatively small. When such a needle is attached to the barrel of the syringe by means of its hub, the syringe is properly balanced so that an operator can manipulate the syringe without muscular 75 strain such as would result from the presence of a massive needle hub. In other words, while the hub has sufficient weight to prevent the point of the needle from tilting downwardly when the needle is placed on a table or the like by itself, it is not so heavy as to throw the syringe out of balance during its use in discharging its liquid contents. Thus the entire weight of a needle, together with its hub, gauge 25, is, for example, in one of the commercial embodiments of the invention 80 1½ dwt. (5/8" needle length beyond hub).

Various changes in the specific form shown and described may be made within the scope 85 of the claims without departing from the spirit of my invention.

Certain parts of the subject matter of this application were divided out of an application heretofore filed by me which has now become Patent No. 1,742,497.

I claim:

1. The combination comprising a hub having a needle end and a butt end, said hub being provided with an interior tapered bore adapted to fit the tapered end of a syringe and to be held thereon by frictional engagement, a needle positioned at the needle end of said hub, and at the furthest outwardly projecting part of the butt portion of the hub, a fin, shaped and dimensioned as a relatively thin lip capable of entering and travelling along a helical groove, the surface of said fin being contoured and adapted for engagement with a flat helically disposed cam surface around and in the path of the fin, the outer surfaces of the hub at two opposed sides thereof in the plane of the fin being nearer the axis of the hub than are the outer edge portions of the fin.

2. The combination comprising a hub having a needle end and a butt end, said hub being provided with an interior tapered bore adapted to fit the tapered end of a syringe and to be held thereon by frictional engagement, a needle positioned at the needle end of said hub, and, at the furthest outwardly projecting parts of the butt portion of the hub, fins projecting from opposite outer faces of said butt portion of the hub, each said fin being shaped and dimensioned as a relatively thin lip capable of entering and travelling along a helical groove, the outer surfaces of the hub at opposed sides thereof intermediate of the fins in the plane of the

130

fins being nearer the axis of the hub than are the outer edge portions of the fins.

3. The combination set forth in claim 1, wherein the hub at the needle end and also at its butt end, at each of two opposed sides of said hub, has portions co-acting in pairs to support the hub in a lying position upon a surface while maintaining the needle out of contact with said surface, the fin being positioned at the butt end of the hub intermediate between the planes of the two pairs of gripping faces.

4. The combination set forth in claim 1, wherein the hub at the needle end and also in the plane of the fin, terminates at each of two opposed sides of the hub in parallel planes, each at its center line being nearer the axis of the hub portions than the outermost part of the fin, the fin being positioned at the butt end of the hub intermediate between the said planes.

5. A hypodermic syringe comprising a barrel provided with a scale and with a plunger, an outlet collar fitted securely on the lower end of said barrel, a sleeve extending from the periphery of said collar, a hollow conical hub projecting from the interior of said collar, a cam way provided in said sleeve, a lug associated with the inner wall of said sleeve and positioned anterior to the starting point of said cam way, a needle having an opening at the lower end thereof and a cam at the upper end thereof adapted to coact with said cam way, and means incorporated in said cam to engage and cooperate with the aforesaid lug to guide the cam into the starting point of said cam way which is so positioned with relation to the cam that the needle opening will be in alignment with the scale when the needle is in its final locked position.

6. The combination comprising a hub having a needle end and a butt end, said hub being provided with an interior tapered bore adapted to fit the tapered end of a syringe and to be held thereon by frictional engagement, a needle positioned at the needle end of the hub and, at the furthest outwardly projecting part of the butt portion of the hub, a fin shaped and dimensioned as a relatively thin lip capable of entering and traveling along a helical groove, the outer surfaces of the hub at two opposed sides thereof extending toward the other end of the hub, said surfaces being spaced apart by a distance which is not as great as the distance between the outermost parts of the said fin and, in the plane of the fin, being nearer the axis of the hub than are the outer edge portions of the fin.

7. The combination comprising a hub member, a tapered bore incorporated within said hub and adapted to make a frictional engagement with a nozzle of a syringe, a transverse fin located at one end of said hub and

having a pair of opposed flat sides, said fin being provided with a plurality of lips extending outwardly farther than the outermost parts of said flat sides and constituting a cam which is capable of entering and traveling along a helically grooved cam way, a pair of opposed flat surfaces provided at the other end of said hub in alignment with the aforesaid flat sides and having such a width as to afford an adequate finger-gripping portion and to provide a stable base, and a needle member projecting from said hub at a point adjacent to said flat surfaces.

8. The combination comprising a hub member, a tapered bore incorporated within said hub and adapted to make a frictional engagement with a nozzle of a syringe, a transverse fin located at one end of said hub and having a pair of opposed flat sides, said fin being provided with a plurality of lips extending outwardly farther than the outermost parts of said flat sides and constituting a cam which is capable of entering and traveling along a helically grooved cam way, a slot formed in one of said lips and adapted to engage a mating lug on the sleeve of a syringe, a pair of opposed flat surfaces provided at the other end of said hub in alignment with the aforesaid flat sides and having such a width as to afford an adequate finger-gripping portion and to provide a stable base, and a needle member projecting from said hub at a point adjacent to said flat surfaces, and having an inclined face and opening in alignment with one of the flat surfaces.

In testimony whereof I have hereunto set my hand.

FAIRLEIGH S. DICKINSON.
